UNITED STATES PATENT OFFICE

ALFRED CLEMENT COTY AND THOMAS EARL COTY, OF WATERTOWN, NEW YORK

PAPER-BAG BOTTOMER

Application filed May 17, 1928. Serial No. 278,459.

Our present invention relates to the paper bag industry and especially to machines for forming the bottom upon paper bags, for which reason we have called it a paper bag bottomer. While it is adapted to the manufacture of bags of various sizes, such as may be required in many industries, it is particularly suited to the handling of large bags made of heavy material, such as those used 10 for cement and flour, in which it is very desirable to have the bottom of the bags formed so as to prevent leakage. While machines have been on the market for that purpose, we believe that our device has substantial advantages over those known to us.

In the manufacture of the larger bags, a system has been increasingly employed in which the tube is formed from paper and the bags cut off to an appropriate length 20 therefrom in a single machine; these are then stacked in a magazine of another machine, and by some feeding device are fed into the other machine for the purpose of forming the bottoms. A feeding device for bags of the 25 character described is shown in our Letters Patent 1,668,761, issued May 8, 1928; we have embodied a feeder of that type in the present machine for forming the bottoms. In our present machine, therefore, blanks of 30 a desired length are stacked in a magazine at one end of the machine, and are then fed into it for forming the bottom. In general, this operation of forming the bottom is performed in a way common in this art, that is, 35 the thumb-notch and projecting tab caused by the formation of the thumb-notch are already embodied in the bag-blanks, and after a blank has been selected from the magazine and fed into the present machine, slits are 40 then cut at appropriate points in the material. The end of the bag is opened and the sides folded in, after which paste is applied and the two flaps are folded over and pressed into place. Of course, this system 45 of operation is old and well-known in many forms of machines, and our improvements consist in means for performing these operations which are new in themselves so far as we are advised, and effect the operation 50 with great speed and accuracy. In machines

which we have built and operated in practice, the feeds are greater than any with which we are acquainted. The quarter-barrel size of the machine, making a bag from 16 inches to 40 inches long and from 12 $\frac{1}{2}$ 55 to 20 inches wide, can be run to turn out 150 bags per minute, the speed which we guarantee to purchasers being 125 per minute for all-day output.

The novel features of our new machine 60 we will point out particularly in the claims, but briefly they are as follows:—

We employ two independent creasers to form the necessary creases on the bottom of the bag instead of using two creasers upon 65 a single cylinder, as has been frequently done heretofore; the timing of this device is such that the creases are formed consecutively at an appropriate distance apart, and this prevents puckering of the rather stiff paper 70 employed in the larger bags. As another feature of this device we have a notch-roll of diameter an aliquot part of that of the sweep of the blade, whereby the notch in one of these creaser rolls makes two revolutions 75 for every stroke of the creaser; we thus get an added clearance, which is desirable for the high speed of the machine.

Another important feature is the use of 80 a large cylinder for folding, and placing a plurality of sets of folding mechanisms, hereinafter called the folding arms, upon the inside of the cylinder, so that instead of pressing the bag inward against the outer periphery of the cylinder, the arms act to 85 press the folds of the bag from the inside toward the outside, so that the folds are pressed against the fabric of the bag itself, means being employed to hold the bag under tension so as to afford sufficient resistance. 90 By doing this we obtain with high delivery speed a relatively slow speed of the folding arms, so that the flaps are not snapped over after the paste is applied with so much speed 95 as is the case in former machines, thus preventing the spattering of paste; while any paste that may be thrown lodges against the bag itself on the inside, where it will be covered by the flap after the latter is folded over. These folding arms employ two move- 100

ments, one turning over the flap and another pressing it firmly into place, and in this respect are like the folding arm which is shown and claimed in our parallel pending application No. 723,031, filed June 28, 1924. The 5 arrangement is one of relatively long period, since while the bag is being carried forward by the cylinder the arm may be pressing upon the flap until the cam releases the arm after a period of approximately 120 degrees 10 of cylinder revolution.

Another feature is the employment of double stationary cams with a cam-roller mounted upon the outer periphery of the cam to give the movement of translation of the folding arm referred to, and another cam roller moving in a groove in the face of the cam to give the movement of pressure for holding the flap down until the paste is set. 15

Another feature is the use of a plurality 20 of folding arms in the large cylinder referred to, so that the cylinder may be run at a moderate speed, and yet the output will be large because of the duplication or multiplication of these devices. 25

Another feature of improvement lies in an automatic stopping device by means of which the absence of a bag from a selected part of the machine will release a detent and bring into action means for stopping the 30 machine, so as to prevent piling up of defective and mutilated bag blanks, and, throwing the operations out of their proper sequence. This device shifts the belt on the machine 35 from the fast to the loose pulley and may apply a brake, if desired.

Another improvement lies in means for dropping the paste-pad out of registry with the bag at the same time that the machine 40 stops, so that paste will not be applied to any blank which happens to be fed into the machine; it being obvious that a large and heavy machine cannot be stopped instantaneously by any device without danger. This 45 prevents spoiling of bag blanks, which are too costly to be wasted. When the machine is running properly, the paste-pad resumes its usual position in registry with the bag on its opposing roll.

Another feature is the provision of ironing rollers at the exit of the machine by means of which any crinkling or creasing of the bags is straightened out before they are delivered to the boxes. 50

The accompanying drawings show one embodiment of the invention.

Figure 1 is a side elevation of a complete machine, some parts of the gearing being omitted for clearness.

Figure 2 shows the gearing of the parts shown in Figure 1.

Figure 3 is an enlarged side elevation, partly in section, of some of the parts shown in Figure 1, with some of the parts omitted 65 for clearness.

Figure 4 is another enlarged side-elevation, partly in section, of the mechanism shown in Figure 3, but in a different position.

Figure 5 is an end elevation of some of the parts shown in Figure 3. 70

Figure 6 is an enlarged detail of the mechanism for shifting the belt from the fast to the loose pulley, which is operated by parts shown also in Figure 5.

Figures 7 to 10 are enlarged details of the 75 paste-pad thrown off, operated in conjunction with the mechanism for stopping the machine automatically when a bag is not in its proper place in sequence.

Figure 8^a is a perspective sketch of the 80 mechanism for dropping the paste-pad at the time when the machine is stopped.

Figure 11 is a side-elevation, partly in section, and upon a larger scale, of the folding mechanism for folding the flaps at the bottom of the bag. 85

Figure 12 is an enlarged detail of one of the folding arms shown in Figure 11, being 85 upon the line 11—11 of Figure 13.

Figure 13 is a plan view of the folding 90 mechanism shown in Figures 11 to 16, and of the ironing mechanism for smoothing out creases in the paper of the bag, shown in Figure 11.

Figure 14 is an end elevation, partly in section upon the line 14—14 of Figure 11, of the folding mechanism shown in Figure 13. 95

Figures 15 and 16 are side elevations partly in section of the folding mechanism shown in Figures 11, 13 and 14, in more advanced 100 positions.

Figures 17 to 19 are perspective sketches showing the end of the bag in various stages of manufacture.

In Figures 1 and 2, A is the frame of the 105 machine provided with a central extension A¹, and a second extension A² on the right, and brackets A³ and A⁴, which carry parts of the apparatus. It will be understood that the frame is so cast for convenience and that the 110 arrangements may be varied. The frame is, as indicated, of heavy cast iron and is provided with flanges for stiffening, so as to form a firm support for the various mechanisms, which are rotated at high speed and necessarily subjected to some strain. B is a 115 magazine containing a pile of blanks C¹. These blanks have been previously formed in a "tuben" and cut off to suitable lengths, after which they are assembled in proper order in the magazine. At various points in the machine single blanks C, C, are shown under operation. To insert a blank in the machine a feeding device, such as is shown in our Letters Patent 1,668,761, dated May 8, 1928, 120 is employed, which is indicated only diagrammatically in Figures 1 and 2 and is shown in a little more detail in Figure 3. This bears the reference character D. There seems to be no necessity for describing this more fully, 125

130

since it is so described in our patent referred to. This is operated by the gear D^1 , provided with adjustments so as to alter the timing of the feeding device as may be required, which is shown in Figures 1 and 2. As this is not the subject of any claim in this application no further description of it will be given.

After leaving the feeding device, as seen best in Figure 3, the bag-blank passes between the feeding rollers E , E^1 , F , G (more fully described later) and is engaged by the belt or tape l , running between the rolls H and G . The bag is carried by the belt over the supporting roll H^1 , around the roll K^2 , which it will be seen is provided with a notch into which the creaser-blade K enters for forming the first or rearmost crease in the bottom of the bag, after which it passes up between the roll K^3 and a second creaser-blade K^1 , which forms a second crease in the bag, turning the flaps up at a substantial angle to the bag in the well-known way. The bag is then engaged between the sets of belts l , l^1 , one of which, the belt l , passes around the roll L ; thence around the cylinder M , which carries the folding blades for the opposing flaps of the bag, then passes out of the machine through the ironing roller N , presently to be described. The belt l passes around the roll L^3 , the roll L^1 and the roll L^2 back to the roll L ; while the belt or tape l^1 passes from the bottoming cylinder M around the roll L^4 and roll L^5 back to the roll L^6 . It will be understood that these belts or tapes are in sets which engage with the side edges of the bag so that the central part of the bag which carries the flaps of the bottom is held under a tension against which the folding devices act, as presently to be explained more fully. It will be observed that the rolls L^3 and L^2 at the bottom and top of the machine respectively are carried upon swinging links centered upon the shafts of the rolls L^4 , L^1 , respectively. These are tension devices of well-known form, and may be operated by springs or otherwise, as may be desired.

In passing under the roll K^2 , with which the creaser-blade K for the first crease operates, the bag-bottom passes over the roll I , which, as more fully explained presently, carries the shoe or pad I^1 , which stamps paste upon the flaps. This roll I cooperates with the roll J , which runs in the tank J^2 , containing the paste, the roller J^1 smoothing out the paste on the roller J and removing any excess therefrom. The reference letter N in Figure 1, applied to the bracket A^2 of the frame, is intended to refer to the ironing rollers as a whole, presently more fully explained. At the bottom of the drawings is shown the shaft C , carrying handles O^1 , O^2 , which is a belt-shifting arrangement.

Figure 2 shows the gearing by which the operation of the various parts is effected, a pulley 1 receiving power from a belt 2 to

drive the central shaft. The various gears are designated by the letters applied to the rolls which they operate, and their directions of rotation are sufficiently indicated by the arrows. As all this is well understood by designers of these machines, no further description is necessary.

There are other points of description necessary to a full understanding of the invention, which will be supplied in connection with the other figures of the drawings showing the machine in greater detail. These two Figures 1 and 2 are designed to show the general course of the bag through the machine, and indicate the various operations, without being exhaustively descriptive.

Turning now to Figure 3, we show the parts of the machine which operate before the folding cylinder M acts, on a somewhat larger scale and in more detail. In this figure the letters are as before, the selector D for drawing out the bag from the bottom of the stack C^1 being shown in the same manner as in our Letters-Patent 1,668,761, issued May 8, 1928. This will not be further described, except to say that the blades d , d , are thrust in beneath the pile of bag-blanks C^1 , and depress one of the blanks C as shown here towards the rollers E , E^1 ; the bag-blanks engage with a hook e^2 carried on an arm e of a bell-crank, the other arm whereof is brought under tension by a spring e^1 , forcing a cam-roller contained thereon against a stationary cam E^2 . The timing is such that the bag is held by the hook e^2 , which moves up under the control of the cam so as to engage the bag against the surface of the roll E , and is then carried down against a guide E^3 . When the bag is engaged between the rolls E , E^1 , the hook e^2 is released as its cam-roller descends from the high point of the cam. The roll F carries properly spaced slitting-knives, commonly used in these machines to form slits which enable the bottom of the bag to be turned in by the folding mechanism. These are old and well known.

Passing over the guide E^3 , the bag then proceeds between the rolls F , G . Centered on the shaft of the roll F are two cams F^2 , F^3 ; F^2 is stationary, F^3 revolves with the shaft (see also Figures 4 and 5). The cam F^2 operates the pins f^3 by means of a bell-crank f ; one arm f^6 carries the cam-roller f^1 to cooperate with the cam F^2 . The timing of this cam is such that as the bag C enters between the rolls F , G , the pins f^3 engage the upper layer of the paper, while on the roll G a gripping finger G^4 engages the tab on the lower layer about on the center line of the roller, and the pins f^3 also pierce the web about on that line. As the rolls revolve the walls are pulled apart the proper distance. The pins then release the upper wall, allowing it to drop upon a finger F^4 , operated by means of the link F^5 , which works one arm

of the bell-crank F^1 centered on the shaft f^5 ; F^5 is operated by a cam-roller f^4 operating by the cam F^3 , which is also shown in dotted lines. The cam F^2 may be adjusted 5 by the usual slot and bolt F^9 to give correct timing. The arm or finger F^4 is then pressed down as shown in dotted line position to follow the upper web of the bag by means of the roller f^4 operating on the cam F^3 , the arm holding open the bag until the finger G^4 engages, and then being withdrawn entirely out 10 of the way to avoid danger of tearing the bag. The office of the finger F^4 is to hold up the upper flap of the bag-bottom until about the time that the roller g , travelling on the cam G^2 , lifts the hook G^4 to release the lower flap 15 as it enters between the rolls G and H , at which time the upper flap slides off the finger F^4 , which then returns to its position shown in solid lines, ready for the next bag.

Upon the roll G we have provided an arrangement by which the machine will be immediately stopped if the bag does not maintain its position or if no bag is fed through 20 to the roll. The stationary cam G^2 is composed of two parts, G^{2a} indicating another parallel disk or piece of metal (see the end elevation in Figure 5) having a high point corresponding to that of the other part of the 25 cam. The two may be moved relatively to adjust the position at which the high point of the cam comes into action, and may then be locked in position by the bolt g^4 . This cam operates a bell-crank lever G^8 having an arm G^4 ; a roller g operates the arm of the bell 30 crank as it rotates around the cam G^2 to raise and lower the arm or finger G^4 . Another cam G^9 is also provided with which the cam button g^7 on the lever G^5 operates. The lever G^5 is centered at g^1 and is also a bell-crank, the other arm of which is connected to 35 a pin g^8 (see also Figure 5). Tripping mechanism is centered at G^6 , consisting of a lever G^7 attached to a rod through a link G^8 . This lever G^7 is held against the hub of the cam G^9 and ordinarily is out action. The lever G^5 is provided with a toe g^2 and is pivoted at g^1 , as already stated.

The operation of these parts is as follows: 40 When a bag, carried between the rolls F and G , is engaged by the gripping finger G^4 , it is under tension and presses down on the pin g^3 (see also Figure 5). That holds the hook g^2 on the end of the lever G^5 out of contact or registry with the point of the lever G^6 , and as long as the bag is thus present to hold down the pin the machine continues to operate. If, however, no bag should be fed into the machine, then the pin g^3 projects 45 beyond the periphery of the cylinder G ; the hook g^2 drops and engages with the lever G^6 , swinging it around its center and lifting the link G^8 to throw the machine out of gear. Of course, if desired, there may be a brake 50 operated by this apparatus, but we have not

deemed it necessary to illustrate or describe that, because such devices are well known. The bag, as already indicated, now passes out from between the rolls G and F to belt l^1 and rolls H^1 , H^2 , and on to the point where the paste is applied to it. It then passes between the paste-pad I^1 , more fully described in connection with Figure 4, and up between the roll K^2 carrying the notch k and the first creaser-blade K . It will be observed 70 from the positions of the blades that the actions of the two creaser-blades are consecutive and not simultaneous, as we have found by this action there is less tendency to crumple the bag and cause it to move out of the plane of operation. It then passes on between the rolls K^3 and belt l^1 , while the second creaser-blade K^1 comes into co-action 80 with notch k^1 in the roll K^3 . It will be seen that the diameter of the roll K^3 is an aliquot 85 part of that of the roll K^1 , in this case one-half, so that the roll K^3 makes two revolutions for every revolution of the creaser-blade K^1 , thus presenting the notch k^1 twice for every revolution of blade K^1 , at one time 90 the blade registering with the notch and at its other appearance the blade being 180° away; by this arrangement we get sharper entrance and exit, with better clearance. The same arrangement may be used with the blade 95 K , if desired.

Turning now to Figure 4 we show some of the same parts as shown in Figure 3, but in somewhat different position. In this case there is no bag between the rolls F and G ; the pin g^3 has been projected beyond the periphery of the roll G , the arm G^5 has descended until the hook g^2 engages with the lever G^7 . The further progress of the roll G presses on the lever, which is pivoted at G^6 , and raises the link G^8 in order to throw the belt and stop the machine. A cam-button g^7 carried upon the arm G^5 is operated by the stationary cam G^9 , and withdraws the hook g^2 when the high part of the cam G^9 is reached. It will be obvious that this action does not restore the belt to the fast pulley, however, as will be apparent from Figure 5 and others. Attached to the link G^8 in any suitable way, as by a collar and bolt H^2 , is another link H^3 operating a lever H^4 , by means of the adjusting nuts H^5 ; the lever H^4 is pivoted at H^6 on a stud shaft affixed to the frame and of course is not attached to the roll H^1 as might be inferred from Figure 4 alone. This lever H^4 has a notch or hook H^7 co-operating with a sliding pin I^6 in a stationary cam I^7 , the lever being held by a spring h (see Figures 7 to 10). The paste shoe I^1 is pivoted at i and is controlled by a toggle I^2 . When the arms of the toggle are straight the shoe is in the elevated position shown in Figure 4, but when the toggle is collapsed the shoe drops out of contact with the bag carried on the roll K^2 , 100 so that when the machine stops the paste-pad 105 110 115 120 125 130 135

or shoe is immediately withdrawn, preventing marring of any bag which may be in the machine. The further detail of this is best understood from Figures 7 to 10. In these figures a stationary cam I^7 is fixed to the frame of the machine. Passing through the cam is a sliding pin I^6 which is engaged by the hook. The position of the pin I^6 is determined by the cam I^8 , which rotates with the shaft I^{13} to which it is attached (see Figures 8 and 8^a). This cam has a high part I^9 which restores the pin to registry with the hook-shaped part H^7 of the lever H^4 at every revolution.

Turning now to Figure 7, which must be read in connection with the other figures, it will be seen that the toggle I^2 has been collapsed, because in this figure the hook H^7 has been withdrawn from the pin I^6 and the pin has been shot in towards the cam I^8 . In so doing it is brought into the path of an arm I^{10} of a bell-crank, the other arm of which is marked I^6 and is notched or shouldered to engage with a detent i^{10} upon the other toggle member I^{2a} . As shown in Figure 4, when the toggle is set the arm I^6 holds the toggle in place against the tension of a spring i^4 . When the toggle is set the shoe I^1 is elevated to the position shown in dotted lines in Figure 7, or in solid lines in Figure 4; at this time the pin I^6 does not register with the other arm I^{10} of the bell-crank, of which the detent or pawl I^6 is a member. When the machine stops and the hook H^7 permits the pin I^6 to be shot inward by the spring i^7 , the arm I^{10} is engaged by the pin, the detent I^6 is withdrawn from the corresponding detent i^{10} on the toggle and the spring i^7 collapses the toggle. All of these parts are carried upon an arm I^{11} shown in Figures 7, 8^a and 10. As the roll I rotates, the cam roller I^{2a} at the joint in the toggle moves around the cam I^7 , and the toggle is straightened to restore the shoe I^1 so that it will register with the bag as it comes through. At the same time the high part I^9 of the cam I^8 restores the pin I^6 so that the hook H^7 enters the reduced portion or notch I^6 and holds it back out of registry with the arm I^{10} . Of course in the meantime the defective bag, if any, has been removed and the operator has restored the sequence of feeding, so that the machine is ready for operation as soon as the belt is shifted. The parts are shown best in their several relations in the perspective sketch in Figure 8^a.

Referring now to Figures 5 and 6, the operation of the belt shifter is indicated. The bar Q shifts the belt marked 2 and is held under tension by the spring q , which tends to push it to the left, so as to throw the belt 2 by means of the fork Q^2 from the fast pulley I^a to the loose pulley I^b . The bar is held from movement by a notch q^4 , in which a pin q^3 registers. The pin q^3 is upon the link Q^1

pivoted at q^2 and having a detent q^6 formed upon an elbow integral with the link Q^1 . The arm O^1 on the shaft O has a hub provided with a notch q^5 , which is engaged by the detent q^6 , the arm being fixed upon the shaft O , and carrying a crank, which in turn carries a pin q^7 which works in a slot in the rod or link Q . The operation of these parts is as follows: When it is desired to stop the machine by shifting the belt the handle O^2 is raised, whereupon the notch q^5 presses upon the detent q^6 , lifts the link Q^1 , so that the pin q^3 is lifted from the notch or detent q^4 in the rod Q , whereupon the spring q forces the rod to the left through the fork Q^2 to the left, and moving the belt from the fast to the loose pulley. When the automatic stop arrangements shown in connection with the roll G are brought into operation, the link G^8 , by means of the collar G^{10} , will lift the link Q^1 (see Figures 5 and 6) and withdraw the pin q^3 from the notch q^4 to effect the same operation. It will be seen that the two methods or means of stopping the machine, though connected, are independently operative, the automatic device coming into action whenever a bag is absent from the machine, but not interfering in any way with the stopping of the machine by hand when desired. When the belt is shifted to the fast pulley I^a , seen best in Figure 5, by the hand-lever O^2 , the roll G (Figure 4) begins to revolve, the hook G^5 having been lifted by the cam-button g^7 so that it clears the member G^7 . The position of the pin g^8 at this time may be as illustrated in Figure 4, as a bag will have been inserted between the rolls F and G before the hook g^7 revolves into re-engagement with the member G^7 , the bag thus depressing the pin g^8 . If necessary, bags may be introduced by hand as the machine is "inched" along until the feed begins to work, as is customary in the trade. At the same time the cam I^8 (see Figure 8) will revolve until the lift I^9 drives back the rod I^6 against the pressure of the spring i^7 until the hook H^7 engages the notch i^8 , thus restoring these parts to the position shown in Figure 4. The toggle arms I^2 , I^{2a} , then straighten out to lift the paste-pad into registry, as already described.

The bottoming mechanism is shown in Figure 11, which should be read in connection with Figures 13 and 14, 15 and 16. The first three figures show the construction of the folding cylinder M and the latter two show advanced positions of this mechanism.

Figure 12 shows one of the folding arms in detail. I have called the part M taken as an integer a "cylinder", though as seen in Figure 14 in reality it consists of two separate disks between which the bag C is stretched, being carried forward by the pairs of tapes $l-l^1$, the first of which runs upon these two disks and the second upon the rollers L^2 , L^3 , l^30

etc., as already described in connection with Figures 1 and 2.

Referring now first to Figure 11 it will be observed that the creaser-blade K is in the notch k of the roll K². At this time the notch k¹ on the roll K³ is on the part of the roll which has been cut away and the creaser-blade K¹ does not register with it until the bag has moved along such a distance as to make the creaser-blade K¹ register with the notch when the two flaps are at the proper distance apart, as shown at C², C³, on the left side of the cylinder M in the upper part of Figure 11. When the bag is in the position shown in this figure, the lower one of the folding arms M² at the bottom of the cylinder M advances and folds over the rear flap C² and presses it in place, after which by the forward movement of the cylinder the second arm M² at the upper left side of the cylinder in Figure 11 comes forward and presses in place the first fold C³, the first arm M² being withdrawn just before this occurs. These arms are both constructed as shown in Figure 12. In that figure M² is a spring member of steel or phosphor bronze. A hub M⁵ rotates upon a shaft M⁶ and a projection from the hub M^{5a}, carries the presser-blade M² upon a lever M³. The lever is fulcrumed at M⁶ and turns against the pressure of the spring M¹¹, regulated by a nut M¹². The lever is rotated around shaft M⁶ by means of a cam-roller M⁸; pivoted to the hub M⁵ is an arm M⁴, worked by a cam-roller M¹. The position of the hub M⁵ may be adjusted by the nuts M⁴ in a well-known way.

Returning to the upper part of Figure 11 it will be seen that there is a plurality, in this case four, of these arms, arranged in pairs. The cam-roller M⁸ travels upon the outside of one of the cams M¹², M¹³, (see particularly Figure 14) and this controls the movement of the arm M⁴, M^{5a}, around the shaft M⁶. On the other hand the cam-roller M² moves in a groove in the face of the cam M¹², that is, two of these rollers move in the groove of the cam M¹², and two of them move in the groove of the cam M¹³. It will be observed that the cams M¹², M¹³, are held respectively in position by means of bars M⁷, attached to the frame, and their positions may be adjusted by means of the nuts M⁷ working in slots in the bars M⁷. These cams are stationary and are centered upon the shaft M⁶. The four arms M², etc., are mounted on a hub M⁹ (see Figure 14) and each is carried by a disk M¹⁰, the positions of which are independently adjustable by means of bolts, as shown, with reference to the hub M⁹.

The operation of these parts is as follows: As the flaps C², C³, approach the cylinder M a blade M² is carried forward by means of the cam-roller M¹ operating in the groove of one of the cams M¹², M¹³, giving an ordinary movement of rotation around the shaft of a

speed sufficiently great to overtake the flap C² and turn it over. After it is folded in this way the cam-roller M⁸ working on the outside is depressed and forces out the folding plate M² around the center M⁶, so as to press out the flap firmly, thus pressing the flap against the web of the bag C, which as shown in Figure 14, extends from one of the disks M to the other. These disks constitute what we have called for convenience the "cylinder" M. After this flap is folded over the upper left-hand blade M² folds over the flap C³ in a precisely identical manner, in the opposite direction, being first advanced by means of its cam-roller M¹ operating in the groove of its cam, and then pressed out by means of the cam-roller M⁸. These operations are clearly indicated in Figure 15 and 16. In Figure 15 the parts are illustrated as the first flap is about to be folded over; and in Figure 16 the first flap has just been folded over (at the upper right-hand part of the figure), and the second flap C³ is just about to be folded over by the second one of the arms M².

So far as we are advised it is new to fold the flaps against the web of the bags from the inside of the folding mechanism or cylinder, and to press them into place while holding the webs under lateral tension. The advantage of this arrangement is that we are enabled to use a very large cylinder and to employ more than one set of folding arms upon it, working in alternation upon alternate bags. The movement of the cylinder does not need to be so rapid, or give so much centrifugal impetus, as when a smaller cylinder is used, employing only one set of folding mechanisms; and in addition the speed of rotation of the flaps C², C³, about their creases as centers is only moderate, so that they are not snapped over hurriedly and do not throw paste, as is apt to be the case with prior devices known to us. In addition, also, any paste which is thrown will fall directly upon the spot which the flap will cover when it is finally pressed down, and does not scatter around the machine and upon the face of the bag.

Figures 17 to 19 show the bag in its various stages of manufacture. In Figure 17 the paste-pad has printed paste upon the bag ready for folding. In Figure 18 the flap C² has just been bent over on the crease C⁴ and C³ has been bent over on the crease C⁵, as shown in side-elevation in Figure 15 at the top of the folding cylinder M; while in Figure 18 both flaps have been tucked into place and pressed down firmly.

Referring now to Figure 13, the parts are the same as those shown in Figure 14, except for the device N on the right of the figure. Folding fingers M², M², are shown in their proper relation, and the cams require no further description, being entirely intelligible from Figure 14 without description.

The ironing device on the right of Figure 13 consists of a series of rollers N^2 , the rollers being provided with diagonal bands n projecting above their surfaces. These bands 5 are run substantially in contact with one another, or nearly so, and the rollers serve to straighten out any creases which may have been formed in the bag by a sort of pressing operation, the action being to put the bag 10 under tension laterally and while under this tension to press the web from the center toward the sides.

It will be observed that the movement of the folding arms M^2 , M^2 , is somewhat similar to that imparted to the arms K^8 in our 15 parallel pending application. S. N. 723,031, filed June 28, 1924.

We have used herein the term "folding cylinder" as a convenient one to describe a 20 rotatory mechanism employed as an operating part, whether technically a cylinder, or a series of co-axial disks such as is often so designated in the trade, or some other construction.

25 What is claimed is:

1. In a paper-bag machine, means for automatically stopping the machine, such means brought into action by the failure of a bag to feed into a desired position, and 30 means brought into action by starting the machine for restoring the stopping means to an inoperative position.

2. In a paper-bag machine, means for automatically stopping the machine when a 35 bag is absent from a desired part thereof, a paste-pad, an opposing roll therefor and means for retracting the paste-pad out of registry with its opposing roll brought into action by operation of the stopping means, 40 both of said means being automatically restored to inoperative position when the machine is started after the stoppage.

3. In a paper-bag machine, mechanism for automatically stopping the machine at desired times, a paste-pad, an opposing roll 45 therefor, and means for moving the pad out of registry with the roll; such means operated by the actuation of the stopping mechanism.

50 4. In a paper-bag machine, mechanism for automatically stopping the machine at desired times, a paste-pad, an opposing roll therefor, means for moving the pad out of registry with the roll, and means brought 55 into action by starting the machine for restoring the paste-pad to its normal registry with its roll and for putting the stopping means into inoperative position.

5. As a combination of elements in a 60 paper-bag machine, a folding finger located between the axis and the periphery of the cylinder, the said finger having two movements, one substantially concentric with the cylinder, and the other outward from the 65 axis toward the periphery of the cylinder

to press the flap into place after it is folded over; and a cam having a periphery, a roller upon the folding finger moving upon the periphery of the cam to impart one of said movements to the finger, a groove in the face of the cam and another roller on the finger co-operating with the groove to cause the second movement of the finger. 70

6. As a combination in a bag-machine, a folding cylinder, means for carrying the bag under tension upon the periphery thereof, and means acting outward from the axis 75 toward the periphery for folding over and pressing down the flaps of the bag-bottom; such means including a presser finger, and cams for giving the finger two motions, one substantially parallel to the periphery of the cylinder at a speed sufficient to turn over the flap and the other substantially radial so as to press down the flap against the bag 80 under tension while the finger and the cylinder move at substantially the same speed; whereby the flap is first turned and then pressed into secure engagement with the web. 85

7. In a paper bag machine, a folding cylinder composed of disks spaced apart upon a shaft, means co-operating with the disks for holding the web of the bag under tension upon the periphery of the cylinder, and means between the axis and the periphery 90 for first folding over a flap and then pressing it against the web; the said means including a presser finger and means for giving it a circumferential movement to fold the flap and then a radial movement to press it into contact with the web, rotation of the cylinder and the finger during the pressing being 95 substantially the same. 100

8. As a combination in a paper-bag machine, a cylinder upon the periphery of which the web is disposed under tension, separate fingers for folding the flap of the bag-bottom; means for causing one of the fingers to fold over and then press the first flap radially against the web while the finger and cylinder rotate at substantially the same speed; means for withdrawing the first finger, and means for causing the second finger first to fold the second flap and then press it radially against the web, the finger and cylinder rotating at substantially the same speed during the pressing. 110

Signed at Watertown, in the county of Jefferson and State of New York, this 7th day of May, A. D. 1928.
